MACHINE FOR SKIVING SHOES AND SOLES

Oliver W. Bodie, Hammond, Ind., assignor to
Walter Boedeker, Chicago, Ill.

Application April 27, 1933, Serial No. 668,199

6 Claims. (Cl. 12—17)

My invention relates to a machine for skiving the worn sole of a shoe which is to be repaired and also for skiving the half-sole which is to fit the stump of the old sole for completing the repair job.

Among the objects of my invention are the following:

To create a machine which will not only skive the worn sole of a shoe which is to be repaired but also skive the new half-sole which is to fit into the skived stump of the old sole to form the completed repair job.

To provide a structure which will prevent the soles from twisting and turning while they are being skived.

To provide a machine for skiving soles on shoes as well as new half-soles so that the two parts skived by the same machine may perfectly inter-fit so as to form a smooth and perfect joint.

To provide a machine which will permit the skiving of the worn sole on the shoe to be the exact length of the new sole which is to replace the worn-out portion of the old sole.

To supply a machine for skiving the old soles on shoes wherein only that portion of the sole may be cut as needs to be skived.

To create a machine with means for adjusting the blade to desired skiving widths and to take care of different thicknesses of leather automatically.

To create a machine having an accessible blade and other parts for adjustment and replacement.

To provide an instrument simple in design, economical of manufacture, easy to assemble and replace worn parts, and such other objects, advantages and capabilities as will later more fully appear, and which are inherently possessed by my invention.

While I have shown herein preferred embodiments of my invention yet I wish it understood that the same is susceptible to modification and change without departing from the spirit of my invention.

Referring more particularly to the drawing:

Fig. 1 is a plan view of a preferred embodiment of my invention; Fig. 2 is an end view; Fig. 3 is a side view; Fig. 4 is a cross-sectional view on line A—A of Fig. 3; Fig. 5 is a cross-sectional view on line B—B of Fig. 4; Fig. 6 is an end view and Fig. 7 a side view of the blade holding means.

The preferred embodiment selected to illustrate my invention comprises a support 10. This support 10 may be the bench to which my ma-

chine is attached or it may take the form of a wooden block or any suitable holding surface.

I employ preferably a stationary body member 11 having a base 12; said base 12 lying on the support 10. Continuing upwardly and at an angle from base 12 is a table 13. The table 13 is triangular in cross section or wedgeshaped. The wide portion 14 is for the necessary strength of the structure while the tapered narrow portion 15 is so formed for the reception of a shoe.

Preferably integral with the body member 11 and adjacent the base 12 is a hinge 16. A pressure member 17 has a pair of spaced arms 18A and 18B and a cross member 19. Adjacent the bottom end of each of spaced arms 18 is opening 20 through which passes pin 21. The pressure member 17 is so placed that the spaced arms 18 at the bottom portion are positioned on either side of hinge 16 so that the pin 21 passes through both arms 18 and through a corresponding opening 22 in hinge 16. Another opening 23 substantially at right angles to opening 22 permits the insertion of a set screw 24 as far as pin 21 to prevent its removal or dislodging.

In cross member 19 is an aperture 25 corresponding with an aperture 26 in table 13 through both of which apertures extends a bolt 27. A resilient member 28 is placed between the head of bolt 27 and the cross member 19. Body member 11 and pressure member 17 are spaced adjacent cross member 19 by a stop member 29. Adjacent the upper portion of arms 18 and placed between said arms 18 is a feed roller 30. This feed roller 30 is fixed between said spaced arms 18 by means of a suitable shaft 31 with which it revolves. One of the spaced arms 18B at its upper end has a boss 32 on a plane with the shaft 31 and acts as a bearing for said shaft 31 and ratchet means or the like 33.

At the top of the arm 18A which is adjacent the tapered portion 15 of body member 11 is an ear 34. This arm 18A is preferably longer than the opposite arm 18B and extends above the feed roller 30.

A holding member 35 is supported at one end 45 to ear 34 by means of a bolt 36 and at the other end by means of a bolt 37 to an extension 38 of body member 11. A blade 39 is attached preferably to the back of the holding member 35 by means of a screw 40, so that the cutting edge 41 of the blade 39 extends down to the upper end of table 13 and opposite the feed roller 30. The blade 39 is preferably placed at such an angle that one side of the edge 41 engages the table 13 at its wide portion 14 while the other 55

side of edge 41 is free and space intervenes between the edge 41 and the tapered portion 15 of table 13. A projection 42 on the arm 18A prevents the edge 41 from extending into the feed roller 30. The holding member 35 has a pair of apertures 43 adapted to hold sleeves 44. These sleeves 44 leave openings 45 of greater diameter than that of the bolts 36 and 37. By placing the holding member 35 in the desired position the angle of the blade 39 may be adjusted to one of several angles because of the play between the bolts 36 or 37 and opening 45. A screw 46 placed in the top of holding member 35 and over the top edge of blade 39 acts as a stop and prevents the dislodging of the blade 39. The arm 18A adjacent the tapered portion 15 of the table 13 has an inclined guiding edge 47. At the upper end of the tapered portion 15 of the table 13 is a convex portion 48. This convex portion 48 is immediately adjacent feed roller 30 and may have slots 49 preferably constructed at right angles to the teeth 50 on feed roller 30.

In use the operation of my invention is extremely simple and practical. Let us assume that we wish to repair a shoe. The shoemaker takes a half-sole to be later applied to the shoe and skives it to the desired length. He places the half-sole on the shoe and marks where the old sole of the shoe is to be skived. He then takes the old shoe and unloosens the front part of the worn-out sole. He need only unloosen up to the point where he has previously marked and desires the old sole to be skived. He then inserts the sole to be skived on table 13 and is guided by arm 18A. He then moves it up toward the feed roller 30 and blade 39. The ratchet means is operated manually and operates the feed roller so as to force the sole to be cut over the convex portion 48 and against blade 39. The convex portion 48 with its slots 49 acts to prevent the shoe from twisting and turning and allows the feed roller to place the sole fairly and squarely against the blade 39. The blade 39 then skives the sole at the desired point.

Having thus described my invention, I claim:

1. A skiving machine comprising, a support, an inclined receiving member fixed to said support and adapted to hold a shoe having a sole to be skived, a hinged pressure member, a feeding member carried thereby, means for operat-

ing said feeding member, a cutting member, and a convex portion on said receiving member adjacent the feeding member having slots substantially at right angles to corrugations on said feeding member.

2. A skiving machine comprising a support, a table fixed to said support and adapted to hold a shoe having a sole to be skived across its width, a hinged pressure member, a feeding member carried thereby, means for operating said feeding member, and a cutting member for skiving across the sole of a shoe.

3. A skiving machine comprising a support, an inclined table fixed to said support and adapted to hold a shoe having a sole to be skived across its width, a hinged pressure member, a feeding member carried thereby, means for operating said feeding member, and a cutting member for skiving across the sole of a shoe.

4. A skiving machine comprising a support, an inclined receiving member fixed to said support and adapted to hold a shoe having a sole to be skived across its width, a hinged pressure member, a feeding member carried thereby, means for operating said feeding member, a cutting member for skiving across the sole of a shoe, and a convex portion in said receiving member adjacent the feeding member.

5. A skiving machine comprising a support, a table fixed to said support and adapted to hold a shoe having a sole to be skived across its width, a hinged pressure member, a feeding member carried thereby, means for operating said feeding member, a holding member, and a cutting member for skiving across the sole of a shoe held by said holding member, said holding member having means to allow adjustment of said cutting member.

6. A skiving machine for soles of shoes comprising a support, a table fixed to said support and adapted to hold a shoe having a sole to be skived across its width, a hinged pressure member, a feeding member carried thereby, means for operating said feeding member, a resilient member on said hinged pressure member for maintaining pressure on said feeding member, means for operating said feeding member, and a cutting member for skiving across the sole of a shoe.

OLIVER W. BODIE.
